UNITED STATES PATENT OFFICE

2,217,852

DOOR MECHANISM

Nelson F. Anderson, Los Angeles, Calif.

Application June 16, 1938, Serial No. 214,165

5 Claims. (Cl. 43—59)

This invention relates to a door mechanism, and it is primarily an object of the invention to provide a mechanism of this kind which normally maintains the closure member in open position and wherein is comprised means for automatically releasing said member to permit the same to move into closed position.

Considerable loss is suffered daily as a result of the picking up and taking away by unauthorized persons of various articles within the home, the store or the like. It is another object of the invention to provide means whereby egress from a room is automatically closed upon unauthorized lifting or displacement of an article within such room.

Furthermore, it is an object of the invention to provide a mechanism which operates automatically to effect the desired closing of an opening to a room or the like, together with means operating in advance of the closing of such opening to give warning to a person outside of the room or chamber that the opening is about to be closed.

The invention consists in the details of construction and in the combination and arrangement of the several parts of my improved door mechanism whereby certain important advantages are attained and the device rendered simpler, less expensive and otherwise more convenient and advantageous for use, as will be herein-after more fully set forth.

The novel features of my invention will herein-after be definitely claimed.

In order that my invention may be the better understood, I will now proceed to describe the same with reference to the accompanying drawings, wherein:

Figure 1 is a view partly in section and partly in elevation and of a diagrammatic character illustrating a mechanism constructed in accordance with an embodiment of my invention;

Figure 2 is an enlarged detailed sectional view taken substantially on the line 2—2 of Figure 1;

Figure 3 is a fragmentary detailed sectional view taken substantially on the line 3—3 of Figure 1;

Figure 4 is a fragmentary detailed sectional view taken substantially on the line 4—4 of Figure 3;

Figure 5 is a fragmentary detailed sectional view taken substantially on the line 5—5 of Figure 1;

Figure 6 is a fragmentary detailed sectional view taken substantially on the line 6—6 of Figure 1;

Figure 7 is an enlarged view partly in section

and partly in elevation illustrating in detail the construction and mounting of the article control lever and parts directly associated therewith, certain of the parts being indicated by broken lines in a second position;

Figure 8 is a fragmentary detailed sectional view taken substantially on the line 8—8 of Figure 1;

Figure 9 is a view substantially the same as Figure 8 but showing the holding member in working position;

Figure 10 is a fragmentary sectional view taken substantially on the line 10—10 of Figure 1;

Figure 11 is a fragmentary sectional view taken substantially on the line 11—11 of Figure 1.

As disclosed in the accompanying drawings, R denotes a room or chamber of any desired dimensions and which may be comprised in any type of building structure. This room R, as illustrated in Figure 1, has an entrance opening A. While the accompanying drawings illustrate but a single opening A it is to be understood that as many openings may be provided as deemed necessary but for the purpose of disclosure it is thought that the showing of only a single opening A is sufficient as the mechanism associated with each of the several openings will be substantially the same.

In the present embodiment of my invention the opening A constitutes a door opening with which is adapted to be employed a conventional door D. The jambs 1 of the casing for the opening A at substantially their transverse centers are provided with the slots 2 herein disclosed as extending from top to bottom of the casing and within the wall structure W and spaced rearwardly from each of the jambs 1 is a vertically disposed strip 3. To each of these strips 3 are suitably affixed the guideways 4 with which slidably engage the vertical marginal portions of a closure member C. These guideways 4 also extend a considerable distance up above the door opening A and the header structure 5 for the opening A is so constructed as to permit the closure member C to be raised entirely above the opening A. This closure member C may be of any construction preferred, it only being required that it be of a material which cannot be easily destroyed because this closure member C when in its lowered or closed position provides an effective medium to prevent the escape of a person within the room or chamber R.

The closure member C is maintained in its normally raised position by the plates 6 fixed to rotate with the vertically disposed shafts 7. These

plates or strips 6 when in position to underlie and hold up the closure member C also serve to effectively close the portion of the slots 2 below the crown or header structure 5. When the plates 6 are swung to allow the closure member C to move into closed position, said plates swing inwardly of said slots.

The upper end portions of the shafts 7 are provided with the suitably directed rock arms 8 which are pivotally connected, as at 9, with a rigid arm 10. Connected, as at 11, to the arm 10 is a retractile spring 12 which is also suitably secured, as at 14, to a suitable part of the wall structure W. This spring 12 serves to normally maintain the plates 6 in a position to close the slots 2 and, of course, in their position when underlying the closure member C.

In the present embodiment of my invention the arm 10 has coupled thereto, as at 15, a flexible member 16 which is disposed over and depends from a suitably positioned guide pulley 17. This member 16 has its extremity remote from the arm 10 connected, as at 18, to a weighted member 19. This member 19 is engaged with a suitably supported and arranged trackway 20. This trackway 20 is vertically disposed and arranged within the wall structure. As disclosed in the accompanying drawings, this weighted member 19 is normally maintained in its raised position by a latch 21. This latch 21 is adapted to be retracted and released from the weighted member 19 upon energizing the associated electro-magnet 22, as will hereinafter be more particularly referred to.

The weighted member 19 in its fall imposes sufficient pull upon the arm 10 to rock the shafts 7 in a direction to move the plates 6 inwardly of the slots 2 and free of the closure member C whereupon said closure member C will substantially instantaneously drop into closed position. Suitably supported by the wall structure or otherwise as preferred, is a nozzle 23. This nozzle 23 is so constructed and arranged as to direct jets of water in such directions as to strike a person who may be outside of the room or chamber R but approaching and in relatively close proximity to the door opening A to give warning that the closure member C is about to drop. This nozzle 23 is in communication through a pipe line 24 with a suitable source of water supply. Interposed in this pipe line 24 is a normally closed valve structure 25 including an operating member 26 of a rocking type. When the valve structure 25 is closed this operating member 24 intersects the path of travel of an outstanding part 27 carried by the weighted member 19. This outstanding part 27 upon the initial dropping of the weighted member 19 strikes the member 26 from above and swings said member 26 sufficiently to open the valve structure 25 to allow the discharge of the water jets out from the nozzle 23. This coaction between the weighted member 19 and the operating member 26 of the valve structure momentarily retards the continued dropping of the weighted member 19 and such coaction also occurs and is completed before the weighted member 19 has dropped sufficiently to impose pull upon the arm 10. While the elapsing time between the opening of the valve structure and the continuing downward travel of the weighted member 19 is comparatively short, yet there is a sufficient elapse of time to permit the water jets discharged from the nozzle to give warning to a person outside of the room or chamber approaching the door opening A that the closure member C is about to fall.

The particular advantage of employing a water jet as a warning medium is due to the fact that upon an unexpected discharge of water upon a person the natural tendency of the person is to jump backward.

In the accompanying drawings the room or chamber R is shown as having therein a suitably positioned shelf 28 upon which desired articles are adapted to be placed either for display, or storage, or as otherwise may be desired. While in the accompanying drawings a shelf is illustrated it is to be understood that I do not wish to be understood as limiting myself in this particular respect as my improved mechanism is equally efficient if employed with various kinds of supporting mediums, it only being required that the supporting means be such that an article 29 placed thereon or supported thereby maintains ineffective a release lever 30.

As herein disclosed the release lever 30 comprises an elongated member provided at its outer extremity with an angularly disposed extension or arm 31 provided at its outer end with a head 32 flattened to conform to the upper surface of the shelf 28. It is to be understood, however, that this head 32 is to be otherwise shaped in accordance with the supporting element with which it may cooperate.

The lever 30 is slidably engaged with an up-standing arm 33 of a bell crank lever 34. The lever 30 is held in desired selective adjustment with respect to the arm 33 by a binding screw 35 or the like. The bell crank lever 34 has its heel portion pivotally supported, as at 36, and the outer extremity of the second arm 37 of the bell crank lever 34 has pivotally connected therewith, as at 38, a latch arm 39. The pivoted portion 40 of this latch arm 39 is weighted so that the same normally swings downwardly but the extent of such downward swinging movement 40 is limited by contact of the tail portion of the arm 39 with a suitably disposed stop 41.

Suitably supported adjacent to the latch arm 39 is a vertically disposed guideway 42 herein disclosed as of a material conductive of electricity and with which slidably engages a contact member 43. The upper portion of this contact member 43 is provided with a lip 44 which, upon upward movement of the contact member 43, will readily pass the latch arm 39. The lip 44 then engages from above the latch arm 39 to suspend the contact member 43 in its raised position until released.

An article placed upon the shelf 28 and contacting with the head 32 of the lever 30 serves to hold the contact member 43 in its raised position but upon lifting of the article 29 the resultant overbalance at the latch arm end of the bell crank lever 34 will result in the latch arm 39 swinging downwardly sufficiently to allow release of the contact member 43. This contact member 43 upon release will drop down and engage a second contact 45 suitably positioned and arranged. This contact 43 has leading therefrom a leg a for the operating circuit for the electro-magnet 22. The electro-magnet 22 is grounded through the leg b while the guide member 42 is grounded through the leg c. Therefore, upon engagement of the contact member 43 with the contact member 45 the electro-magnet 22 will be energized retracting the latch 21 and permitting the weighted member 19 to drop.

During such times as it may be desired to make the mechanism ineffective, as for example during working hours or at the time the room or cham-

ber R is under proper surveillance, a holding rod 46 is caused to engage under the arm 37 of the bell crank lever 34 whereby said arm is effectively held against downward swinging movement which otherwise would result in the release of the contact member 43. This rod 46 is so positioned that after it has been moved to underlie the arm 37 said arm 37 will have limited downward movement to rest from above and engage within the holding recess 47 provided in the rod 46. This slight downward movement of the arm 37 results in an upward projection of the arm 31.

This holding rod 46, as herein disclosed, is slidably supported by a suitably positioned bracket 48 and said rod 46 is constantly urged outwardly or in ineffective position by an expansible member 49, herein disclosed as a coil spring, surrounding the rod 46 and interposed between a leg of the bracket 48 and a suitably positioned stop 50 carried by the rod 46. This stop 50 is of a length or formation to engage within an elongated slot 51 provided in the bracket 48. This is of importance as this assures the holding notch 47 at all times being maintained in proper position with respect to the arm 37 of the bell crank lever 34.

Upon the placing of an article 29 upon the shelf 28 and, of course, also on the head 32, the resultant downward movement of the lever 30 will raise the arm 37 of the bell crank lever 34 sufficiently to release the rod 46 whereupon said rod 46 under the action of the expansible member or spring 49 will instantaneously shift into ineffective position.

When an authorized person wishes to remove an article 29 and, of course, to prevent functioning of the mechanism for the closure member C, such person before removing the article pushes the rod 46 inwardly so that it will be disposed below the arm 37 to prevent the same swinging downwardly upon removal of the article 29 to release the contact member 43.

When the closure member C is in its proper closed position it is held therein, as herein disclosed, by the latch bolt 52 positioned within the wall structure and which engages from above an outstanding lug 53 when the closure member C is in its closed position.

The closure member C is effectively held against opening movement until the bolt 52 is disengaged from the lug 53. As illustrated in Figure 11, this bolt 52 extends exteriorly of the wall structure W to provide a convenient means for retracting the same.

While not illustrated it is to be stated that if desired a suitable alarm may be provided which will operate upon closing of the closure member C.

In view of the foregoing it is believed to be clearly apparent that normally the closure member C is hidden and it is also believed to be understood that a portion of the mechanism is concealed within the wall and it is to be further stated that the lever 30 and the parts directly associated therewith are also adapted to be concealed. However, as this concealment forms no part of the present invention and may be accomplished in any way, it is not believed necessary that a detailed description and illustration be given except to state that suitable provision will be made, as for example removable panels to permit access to those parts which initially have to be manually set.

From the foregoing description it is thought to be obvious that a door mechanism constructed in accordance with my invention is particularly well adapted for use by reason of the convenience

and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a wall having an opening, a closure member for said opening, means for mounting said closure member for sliding movement in a vertical direction, said closure member moving upwardly to open position and dropping into closed position, an article supporting member, means for normally maintaining said closure member in its upper open position, and means for releasing said holding means to allow the closure member to drop to closed position, said releasing means including a part associated with the article supporting member for maintaining said releasing means ineffective under the weight of the article supported by said member and allowing said releasing means to become effective upon lifting the article supported by the member.

2. In combination with a wall having an opening, a closure member for the opening, means for mounting the closure member for vertical movement, said member moving upwardly to open position and dropping into closed position, vertically disposed shafts at each side of the opening, means for supporting said shafts for rocking movement, plates carried by the shafts to underlie the closure member when raised to hold the same in such position, an arm operatively connected with the shafts to rock said shafts in unison to swing the plates from beneath the closure member to allow the closure member to drop, means coacting with the arm for constantly urging the same in a direction to maintain the plates below the closure member when raised, a weighted member, means for mounting the weighted member for movement in a vertical direction, releasable means for holding the weighted member raised, a suitably guided flexible connection between the weighted member and the arm, and means for releasing the weighted member to impose pull upon the arm to rotate the shafts in a direction to swing the plates from under the raised closure member to permit said closure member to drop.

3. In combination with a wall structure having an opening, a vertically slidable closure member for said opening, said closure member raising into open position, a movable member engaging under the closure member when raised to hold the same from dropping, a weighted member, a latch for holding said weighted member in raised position, an operative connection between the weighted member and the movable member to provide means to shift said movable member from below the closure member upon dropping of the weighted member to permit the closure member to drop into closed position, an electromagnet for retracting the latch to permit the weighted member to drop, an operating circuit for the magnet, a circuit closer interposed in the circuit comprising two contact members one being movable with respect to the other, a swinging member engaging the movable contact to maintain the same in its separated position, said swinging member having a part upon which a weight is to be placed to maintain the mov-

- able contact in its separated position, said swinging member upon removal of the weight releasing the movable contact for movement into engagement with the second contact.
5. In combination with a wall structure having an opening, a sliding closure member for said opening, means for normally maintaining said closure member in open position, means for releasing said holding means to allow the closure member to move into closed position including a weighted member; a latch for normally holding the weighted member in raised position, an electromagnet for retracting the latch to allow the weighted member to drop to make the releasing means effective, an article supporting shelf, an operating circuit for the electromagnet, a switch interposed in the circuit including two contacts one being movable with respect to the other, a bell crank lever supported for rocking movement, one arm of the bell crank lever engaging the movable contact to hold the same in separated position; a lever carried by the second arm of the bell crank lever and having a part extending above the article supporting shelf when the first arm of the bell crank lever is free of the movable contact, weight imposed upon the support and the part carried by the lever holding the bell crank lever against swinging movement when engaged with the movable contact, release of the weight on the part of the lever permitting the bell crank lever to swing in a direction to permit the movable contact to move into engagement with the second contact.

NELSON F. ANDERSON.
